US00D998648S

(12) **United States Design Patent** (10) **Patent No.:** **US D998,648 S**
Dralle et al. (45) **Date of Patent:** **** Sep. 12, 2023**

(54) **MANIFOLD**

(71) Applicant: **Holley Performance Products, Inc.**,
Bowling Green, KY (US)

(72) Inventors: **James D. Dralle**, Bowling Green, KY
(US); **Corey D. Spainhoward**, Bowling
Green, KY (US)

(73) Assignee: **Holley Performance Products, Inc.**,
Bowling Green, KY (US)

(**) Term: **15 Years**

(21) Appl. No.: **29/713,626**

(22) Filed: **Nov. 18, 2019**

(51) LOC (14) Cl. **15-01**

(52) U.S. Cl.

USPC **D15/5**

(58) **Field of Classification Search**

(57) **CLAIM**

The ornamental design for a manifold, as shown and described.

DESCRIPTION

Cross-reference is made to U.S. Design patent application Ser. No. 29/713,625, titled "Manifold," U.S. Design patent application Ser. No. 29/713,627, titled "Panel for Intake Manifold," U.S. Design patent application Ser. No. 29/713,628, titled "Throttle Body Adapter," all filed on the same day as the present application and all of which are expressly incorporated herein by reference.

FIG. 1 is an upper perspective view of a design of a manifold;

FIG. 2 is a front view of the design of FIG. 1;

FIG. 3 is a rear view of the design of FIG. 1;

FIG. 4 is a first side view of the design of FIG. 1;

FIG. 5 is a second side view of the design of FIG. 1;

FIG. 6 is a top view of the design of FIG. 1;

FIG. 7 is a bottom view of the design of FIG. 1; and,

FIG. 8 is a lower perspective view of the design of FIG. 1.

The broken lines shown in the drawings are included for the purpose of illustrating the unclaimed boundary and unclaimed portions of the manifold. The broken lines form no part of the claimed design.

1 Claim, 8 Drawing Sheets
